DESIGN FOR A DRESS

Harry Roher, New York, N. Y.

Application September 5, 1939, Serial No. 87,039

Term of patent 3½ years

To all whom it may concern:

Be it known that I, Harry Roher, a citizen of the United States, residing in New York city, in the county of New York and State of New York, have invented a new, original, and ornamental Design for a Dress, of which the following is a specification, reference being had to the accompanying drawings, forming part thereof.

Fig. 1 is a front view of a dress showing my design,

Fig. 2 is the rear view thereof,

Fig. 3 is an enlarged fragmentary view of the dress shown in Fig. 1 illustrating the embroidered trim at the neckline; and

Fig. 4 is an enlarged fragmentary view of the dress shown in Fig. 1 illustrating the embroidered trim of one of the pockets.

The characteristic feature of my design resides in the combination on the dress disclosed of the specific, beaded embroidery, arranged about the neckline and on the skirt as shown.

I claim:

The ornamental design for a dress, substantially as shown and described.

HARRY ROHER.
